UNITED STATES PATENT OFFICE.

MILLARD F. FIELD, OF WINTHROP, MASSACHUSETTS.

PICKER-CHECK FOR LOOMS.

No. 859,554.

Specification of Letters Patent.

Patented July 9, 1907.

Application filed May 12, 1906. Serial No. 316,467.

To all whom it may concern:

Be it known that I, MILLARD F. FIELD, a citizen of the United States, residing in Winthrop, in the county of Suffolk and State of Massachusetts, have invented certain new and useful Improvements in Picker-Checks for Looms, of which the following is a specification.

This invention relates to a new and improved checking device adapted to be applied to the lay of a loom, and operating as a direct check for the picker-stick.

10 The invention has for its object to provide a check which will produce the desired increasing resistance on the return or backward motion of the picker-stick and a less resistance on the forward motion thereof, which will prevent rebound, which will be economical with 15 regard to the wear on the stick, and with respect to its own durability, which will be simple in construction and easily replaced, which will require no oil, and which will be easily applied and adjusted.

The present invention relates to that class of picker-checks in which the frictional resistance is applied on a side of the stick, and it comprises a plurality of layers of straps of leather or its equivalent on each side of the path of the stick, such layers on each side consisting of a main layer and one or more supplemental layers projecting into the path of the picker-stick, the main layers having their rear or inner ends directly secured to springs disposed substantially in line with the checking straps.

The nature of the invention is fully described in detail below, and illustrated in the accompanying drawing, in which:

Figure 1 is a front elevation of one end of the lay and adjacent parts of a loom showing my invention applied thereto, the picker-stick being shown at the end of its stroke. Fig. 2 is an inverted plan of the check removed, showing the stick entering the check during its backward movement.

Similar letters of reference indicate corresponding parts.

40 *a* represents the lay, *b* the end-iron thereon, *c* the shuttle, *d* the shuttle-box, *e* the picker and *g* the picker-stick—all constructed as usual.

h represents a double hook-shaped hanger, preferably of strong wire, whose hooked end *h'* catches over the upper edge of the end of the end-iron *b*. The looped lower end of this hanger extends into and under notches *i* in the lower edges of a stout leather strap which is doubled or folded near the notches into two equal horizontal parts *k*. Each of these parts is provided with a horizontal row of vertical slots *n*, and caught in these slots are straps *p* and *s*, each of said straps having its ends provided with projecting tongues *t* which extend into the slots as shown, and thereby retain the straps in position. The straps *p* and *s* are not of equal length,

the shorter strap *p* being between the strap *s* and the 55 main strap *k*. Each supplemental strap has its ends or tongues *t* inserted in holes which are at such a distance apart as to cause the strap to protrude for the desired extent toward or into the path of the picker-stick, the innermost strap being of course that which is to come 60 into direct contact with the stick. Spiral springs *v* have their opposite ends caught in the free ends of the straps *k*, and in suitable eyes *w* in rods *y* extending from the loom on opposite sides of the path of the picker-stick.

65 In operation, the picker-stick on its backward movement presses back the straps *s* on opposite sides with which it comes into contact, and said straps *s* press back the strap *p*, and the straps *s* and *p* operate directly by means of their tongues on the main straps *k*, 70 which spread to a greater or less extent, and at the same time expand to a corresponding degree the spiral springs *v*. Thus there is provided a gradually increasing frictional resistance until approximately the end of the stroke is reached, and then the stick is prevented 75 from rebound. This resistance is regulated according to the conditions, in two ways, viz., by applying additional supplemental straps to the main strap *k*, and by placing the ends of tongues of the supplemental straps into holes which are nearer together, thus causing the 80 straps to protrude farther into the path of the picker-stick.

It will readily be seen that in this device the frictional resistance is not only on opposite sides of the picker-stick but can be regulated to suit different 85 looms, to an exact degree, not only by varying the numbers of supplemental straps and the degree of their projection into the path of the picker-stick, but also by applying stronger or weaker springs.

The resistance as the stick starts on its forward movement is very much less than when it is entering the check near the end of its backward movement, and in fact is but little more than is necessary to prevent rebound.

Having thus fully described my invention, what I 95 claim, and desire to secure by Letters Patent, is:—

1. In a picker-check for looms, a checking device, comprising flexible main straps on opposite sides of the picker-stick, and supplemental straps extending from said main straps into the path of the picker-stick, for the purpose of 100 checking its movement by frictional contact with the sides of the stick.

2. In a picker-check for looms, a checking device, comprising flexible main straps on opposite sides of the picker-stick provided with a series of slots, and supplemental 105 straps whose opposite ends are inserted in said slots, whereby the supplemental straps extend from the main straps into the path of the picker-stick, for the purpose of checking its movement by frictional contact with the sides of the stick.

3. In a picker-check for looms, a checking device, com-

prising flexible main straps on opposite sides of the picker-stick, supplemental straps extending from the main straps into the path of the picker-stick, and springs connecting the inner ends of the main straps with the lay, for the purpose set forth.

4. In a picker-check for looms, a checking device, comprising flexible main straps on opposite sides of the picker-stick, supplemental straps extending from the main straps into the path of the picker-stick, springs connecting the inner ends of the main straps with the lay, an end-iron se-

cured to said lay and a hanger extending from the end-iron into supporting engagement with the main straps, for the purpose set forth.

In testimony whereof I have signed my name to this specification in the presence of two subscribing witnesses. 15
